UNITED STATES PATENT OFFICE.

HARRY ALBERT GRIFFITHS, OF BIRMINGHAM, AND RICHARD HANSON GRIFFITHS,
OF SUTTON COLDFIELD, ENGLAND.

PRESS FOR OPERATING ON METAL SHEETS.

1,415,838.

Specification of Letters Patents.

Patented May 9, 1922.

Application filed August 23, 1921. Serial No. 494,534.

To all whom it may concern:

Be it known that we, HARRY ALBERT GRIFFITHS, residing at 8 Chad Road, Edgbaston, in the city of Birmingham, England, and 5 RICHARD HANSON GRIFFITHS, residing at "Highfield," Sutton Coldfield, in the county of Warwick, England, subjects of the King of Great Britain and Ireland, have invented certain new and useful Improvements Relating to Presses for Operating on Metal Sheets, for which I filed an application for patent in Great Britain 23970, dated Aug. 17, 1920, and of which the following is a specification.

15 This invention relates to drawing and like presses for operating on metal sheets, as e. g. in the manufacture of metal boxes from circular sheet metal blanks. It is usual to arrange with the lower tools a plurality of 20 stops against which the blanks are fed, and by which the blanks are properly positioned relatively to the tools. The stops necessarily project above the lower tools and ordinarily are fixed, and as a consequence it is usually 25 necessary to adapt the upper or movable tools (e. g. by the provision of apertures or channels therein) to clear the stops when they come into action on the lower tools. This condition is undesirable inasmuch as 30 the shaping of the tools to accommodate or clear the stops often results in weakening of the tools, and further additional labour is involved in the production of the tools.

The object of the present invention is to 35 avoid the disadvantages of the ordinary stops, and for this purpose the invention comprises the use of hinged stops which automatically take up the operative position relatively to the lower tools and which re- 40 cede to an inoperative position under the action of the upper or movable tools.

In the three accompanying sheets of explanatory drawings:—

45 Figures 1 and 2 are sectional side elevation and plan illustrating one application of the invention to press tools for operating on circular blanks.

50 Figure 3 is a side view illustrating a modified device.

55 Figures 4 and 5 are respectively similar views to Figures 1 and 2 showing an application of the invention to tools for operating on rectangular blanks.

In carrying the invention into effect as 55 shown in Figures 1 and 2, a pair of brackets

a are secured in convenient positions on the bed of the machine adjacent to the lower tools, which in the example illustrated comprise a central fixed portion b, an outer ring c, the latter being supported by parts d on a spring e. On each bracket is pivoted a segmental or lever like stop f which under the action of a spring g takes up an effective position relatively to the tools. The edge adjacent to the lower tools is arc-shaped in order that it may remain operative throughout a suitable range of angular movement. The blanks as h are fed up to the stops singly in the usual way along a line indicated by the arrow Figure 2. When the upper or movable tool i approaches the lower tools it first engages the stops, and during the remainder of its movement causes the stops to swing about their pivots against the action of the springs, the operative edges of the stops remaining in contact with the blanks throughout this movement. After the shaping operation on the blank, the stops return with the upper tool to the operative position under the action of the springs.

By this invention we are able to avoid in a simple and effective manner the disadvantages above mentioned of the ordinary fixed stops without in any way interfering with the proper positioning of the blanks. If desired the operative edges f' of the stops may be made slightly eccentric or cam shaped as shown in Fig. 1, so that during their movement they impart a slight sliding movement of the blanks for the purpose of accurately centering the latter relatively to the tools.

In some cases it is advantageous to hold the stops in the depressed position, until the upper tool has returned almost to its initial position, particularly where difficulty might otherwise be found in getting the blank after the shaping operation clear of the stops during the return of the upper tool. We then arrange in conjunction with one or all of the hinged stops as shown in Figure 3 a catch lever j which under its own weight or a spring rests on a support k. During the descent of the upper tool a projection l on the hinged stop is caused to engage a notch m on the catch lever; the stop lever is then held until released. In conjunction with the part of the machine carrying the upper tool is arranged a trip member n

which when the said tool approaches the upper limit of its movement tilts the catch lever and releases the stop. Meanwhile the shaped blank has had time to move clear of the tools. The catch lever may be actuated for releasing the stop lever in any other convenient manner.

For dealing with rectangular blanks we shape the hinged stops as shown in Figures 4 and 5. These are arranged at a pair of opposite sides of the lower tools and are adapted to abut against the blank at its front and rear ends. The front end of each stop is splayed out to avoid obstructing the free movement of the blank while it is being inserted in position on the lower tools, and the rear end of each stop is formed with a projection f' which limits the forward movement of the blank. In other particulars the mechanism is essentially the same as that above described. It will be understood that each hinged stop may be provided with a catch lever as shown in Figure 3 if required.

Having thus described our invention what we claim as new and desire to secure by Letters Patent is:—

1. In presses for operating on metal sheets or blanks, the combination with a fixed tool, of a stop pivotally mounted alongside of the said tool and having a stop portion extending into close proximity to the edge of said tool, means for automatically moving the stop to a position where the stop portion projects beyond the operative surface of said tool, and a second tool movable toward and away from the fixed tool and engageable with said stop portion for gradually moving the latter over the edge of the fixed tool 40 when the movable tool is moving toward said fixed tool.

2. A combination as claimed in claim 1 in which the stop portion is provided with a curved surface adapted to move across the edge of said fixed tool.

3. A combination of the kind defined by claim 1 in which the stop portion is provided with an arc-shaped operative surface adapt-

ed to move across the edge of said fixed tool, the arc of said surface being struck from a center arranged eccentrically to the pivot of said stop.

4. A combination of the kind claimed in claim 1 including latching means adapted to engage said stop for locking the same in depressed position while the movable tool is moving toward the fixed tool, and means movable with the movable tool for releasing said latching means after the movable tool has moved away from the fixed tool.

5. In presses for operating on metal sheets or blanks, the combination with a fixed tool, a slidable member surrounding said tool and having its upper surface normally in alignment with the upper surface of the tool, means for urging the sliding member into a position where its upper surface is in the same plane as the upper surface in the fixed tool, standards arranged at the sides of said tool, substantially horizontal arms pivotally mounted on said standards and provided at their outer ends with curved operative surfaces arranged adjacent to the upper edge of said sliding member, means for normally holding the outer ends of said arms in a position where they project above the upper surface of the fixed tool, and a tool movable toward and away from said fixed tool and engageable with the outer ends of said arms for causing the curved surfaces of the same to move across the upper edge of said sliding member when the movable tool descends.

6. A combination of the kind defined by claim 5 including latching means for automatically locking the outer ends of said arms in depressed position after they have been forced to this position by the movable tool, and means movable with the movable tool for releasing said latching means at a time when the movable tool has nearly completed its ascending movement.

In testimony whereof we have signed our names to this specification.

HARRY ALBERT GRIFFITHS.
RICHARD HANSON GRIFFITHS.
